UNITED STATES PATENT OFFICE.

CHARLES P. GOLDSMITH, OF NEW YORK, N. Y., ASSIGNOR TO CHARLES P. GOLDSMITH & CO., OF NEW YORK, N. Y., A FIRM.

DESIGN FOR A CLUTCH FOR SCARF-PINS AND BROOCHES.

40,279.

Specification for Design.

Patented Sept. 28, 1909.

Application filed May 22, 1907. Serial No. 375,177. Term of patent 7 years.

To all whom it may concern:

Be it known that I, CHARLES P. GOLDSMITH, a citizen of the United States, residing in New York, in the borough of Manhattan, county and State of New York, have invented a new, original, and ornamental Design for Clutches for Scarf-Pins and Brooches, of which the following is a specification, reference being had to the accompanying drawing, forming part thereof.

The figure is a side-elevation of a clutch for scarf-pins and brooches, showing my new design.

I claim—

The ornamental design for a clutch for scarf-pins and brooches, as shown.

CHARLES P. GOLDSMITH.
